ELECTRIC FURNACE.

1,202,837.

Specification of Letters Patent.

Patented Oct. 31, 1916.

Application filed February 7, 1914. Serial No. 817,369.

To all whom it may concern:

Be it known that I, INGENUIN HECHENBLEIKNER, subject of the Emperor of Austria-Hungary, and resident of Charlotte, in the county of Mecklenburg and State of North Carolina, have invented certain new and useful Improvements in Electric Furnaces, of which the following is a specification.

10 This invention relates to electric furnaces and particularly to such furnaces as may be used in the manufacture of phosphorus vapors and phosphoric acid by heating phosphate rock with silicious material and 15 carbon.

The objects of the invention are to utilize the heat of the furnace gases to uniformly preheat the charge and to avoid overheating of the brick work, electrodes and other parts 20 of the furnace.

Further objects are to provide improved water cooling means for various parts of the furnace, and generally to improve and simplify the construction thereof.

25 The invention consists of the improved construction hereinafter described in detail in the accompanying specifications and drawings.

In the drawings the figure is a sectional 30 elevation of an embodiment of the invention.

In the drawings like characters of reference indicate corresponding parts in all the figures.

Referring to the drawings, A represents 35 the body portion of the furnace, B the stack, and C the tapered frustoconical portion connecting the body portion with the stack. These parts will be constructed of suitable fire resistant material. I have shown a sheet 40 metal casing D having a lining E of fire brick.

The body portion of the furnace is provided with a water jacket F surrounding the sides and bottom thereof and conveniently 45 constructed of sheet metal reinforced with suitable angle irons and channels. The refrigerant, preferably water, is introduced through suitable pipes 10 at the bottom and withdrawn through other pipes 11 at the top. 50 The inner portion 20 of the water jacket is

connected at the top only with the outer portion 21 whereby it may be free to expand and contract, and may be readily removed for repair purposes. Two vertically separated tap holes 12 and 13 are provided in 55 the body portion for the slag, both being protected by water cooled means.

I have shown two hollow water cooled jackets 14 and 15 for each tap hole telescoping one within the other, and through each 60 of which water is circulated, being introduced through suitable pipes 16 and withdrawn through other pipes 17. The jackets are of frusto-conical shape, the smaller end of one jacket embracing the larger end of the 65 other. The inner jacket is held in position by suitable means, such as a strap 18 on the outer jacket. It will be seen that the inner tap jacket 15 may be readily removed and replaced when it becomes worn out or 70 clogged. Both of the jackets 14 and 15 are embedded in the fire brick lining E.

The electrodes G and H of carbon or graphite extend through the tapered portion C of the furnace and each is surrounded 75 as it passes through the point where it enters the furnace wall with a water cooled jacket I which also serves as a packing box. Each of the jackets 5 is embedded in an extension 26 formed in the side of the tapered portion and may be made from a suitable casting provided with a water inlet pipe 27 and outlet pipe 28. The jacket I is further formed around the electrode with a suitable recess 29 adapted to contain suitable 80 packing 30, preferably asbestos. To avoid any current leakage, the water jackets do not form a connected ring around the electrodes, but are separated at 30 by a break in the annulus to leave an isolated 85 space between the ends.

The electrodes are adjustable with respect to the jacket I, and are also formed with suitable current connectors, preferably of a water cooled type, the construction of which 95 does not form part of the present invention. The electrodes are also adjusted and fed by any suitable or well known means. It will be observed the jackets I extend only part way through the fire brick lining, whereby 100

they are protected on the inner side from the heat and chemical reaction within the furnace.

The raw material is fed to the stack B 5 through a suitable charging bell J and the volatile products of the reactions in the furnace are withdrawn through an outlet conduit K, which leads laterally from one side of the top of the stack.

10 It will be observed that the tapered portion of the furnace is a considerable distance above the electrodes and above the reaction zone, whereby the gases liberated by the reaction will preheat that portion of the 15 charge which is in the tapered portion and stack of the furnace.

It will be observed that as the heat of the furnace gases is reduced the area over which they are distributed is also reduced to 20 correspond, whereby a uniform degree of heating is obtained and the flow of the furnace gases not restricted by the reduction of area. It will also be observed as the electrodes extend through the smooth inclined 25 body portion of the furnace wall no pocket will be formed above the electrodes in which hot gases might collect to overheat either the electrodes or the wall of the furnace. This tapered shape also reduces the pressure on 30 the carbon as the portion of the electrodes within the furnace is not subject to the entire weight of the charge in the stack. The furnace is particularly adapted for use in a process for the manufacture of phosphoric 35 acid in which the material to be furnace 40 d consists of a mixture of natural phosphate rock, silicious material and carbon, and the furnace gases consist of phosphorus vapor, carbon monoxide and phosphoric acid, which furnace gases assist in preheating the charge in the manner already explained.

It is essential in this process in the manufacturing of phosphorus or phosphoric acid, that the temperature shall be well regulated 45 and the intense heat of the electric arc so applied to avoid a local overheating of the charge or of the slag. Overheating of the charge or slag will cause a distillation of not only phosphorus but will also produce a distillation of silicon compounds.

Silicon and silicon compounds are generally the cause of "killing" the phosphorus, or, in case the phosphorus is afterward oxidized for the manufacture of phosphoric 55 acid, said phosphoric acid forms water insoluble, commercially worthless compounds containing SiO_2 and P_2O_5 . To prevent these disadvantages in the process the typical design of the furnace shown is the most important feature. Tests have shown that in 60 the case of this furnace the charge moves regularly and under a steady pressure downward between and around the electrodes. In this way the once melted and reduced slag is

removed quickly out of the dangerous arc 65 zone before overheating can take place. Fresh material replacing quickly the melted slag prevents the formation of hollow spaces between the electrodes and charge, and at the same time prevents overheating of material and distillation of silicon and silicon compounds. It makes no difference whether the material be powdered, granulated or briqueted, if the melting of the material be as described above since no distillation of 75 harmful compounds takes place. The break in the water jacket around the electrode already described is found to be particularly useful for an alternating current.

In the practical operation of the furnace 80 the calcium silicate slag will flow continuously through the upper tap holes 12, while any heavier material, such as iron may from time to time be taken out through the hole 13. Owing to the high conductivity of the 85 hot melted slag and metallic water jacket, it is necessary that the furnace should be thoroughly insulated from the ground.

Having thus described my invention, what I claim is:

1. An electric furnace having an expandible water jacket formed with disconnected parts inclosing the sides and bottom in a continuous manner.

2. An electric furnace comprising a body 95 portion, a water jacket thereon formed with disconnected parts, an uncooled masonry tapered portion formed with integral masonry extensions on the sides, electrodes extending through the extensions, and water jackets 100 for the electrodes extending partially in the extensions and being supported thereby.

3. An electric furnace comprising a cylindrical bottom portion in which the greater part of the reaction is adapted to take place, 105 formed with separated tap holes, a tapered portion above the cylindrical portion and having a wall tapering uniformly inwardly from the same, electrodes extending through the tapered portions and projecting downwardly into the body portion, and a top cylindrical portion formed with a laterally extending conduit integral therewith.

4. An electric furnace comprising a body portion, a masonry tapered frusto-conical 115 portion formed with integral extensions on the sides, a stack above the tapered portion and electrodes extending through the extensions on the tapered portion and extending downwardly into the body portion.

5. In an electrical furnace, a tap hole, two water cooled jackets for the tap hole telescoping one within the other, each of frusto-conical shape, the smaller end of one jacket embracing the larger end of the other, and a strap on the outer jacket projecting over the inner jacket and adapted to hold the inner jacket in position.

6. In an electric furnace, a body portion, a water jacket surrounding the sides and bottom thereof and constructed of sheet metal reinforced with angle irons and channels, the inner portion of the water jacket being connected at the top only with the outer portion whereby it may be free to expand and contract.
- 5 7. In an electric furnace, a water jacket
10 adapted to surround an electrode and adapt-

ed to extend completely around the same, 15
save for a single gap which forms an insulating space between the ends.

Signed at 141 Broadway, in the county of
New York and State of New York this 4th
day of February, A. D. 1914.

INGENUIN HECHENBLEIKNER.
